DESIGN FOR A GAME BOARD

William D. Heintz, Galloway, Ohio

Application November 7, 1947, Serial No. 142,364

Term of patent 14 years

(Cl. D34—5)

To all whom it may concern:

Be it known that I, William D. Heintz, a citizen of the United States, residing at Galloway, in the county of Franklin and State of Ohio, have invented a new, original, and ornamental Design for a Game Board, of which the following is a specification, reference being had to the accompanying drawing, forming part thereof.

Fig. 1 is a top plan view of a game board showing my new design, and

Fig. 2 is an end elevational view from one end. The shaded portions of the drawing indicate contrasting colors.

I claim:

The ornamental design for a game board, as shown and described.

WILLIAM D. HEINTZ.
